UNITED STATES PATENT OFFICE.

JOHN T. LINDSTROM, OF MOUNT VERNON, OHIO.

VALVE MECHANISM FOR ENGINES.

SPECIFICATION forming part of Letters Patent No. 623,251, dated April 18, 1899.

Application filed October 17, 1898. Serial No. 693,761. (No model.)

To all whom it may concern:

Be it known that I, JOHN T. LINDSTROM, a citizen of the United States, residing at Mount Vernon, in the county of Knox and State of Ohio, have invented a new and useful Valve Mechanism for Steam-Engines, of which the following is a specification.

This invention relates to valve mechanism for steam-engines.

10 The object of the invention is to provide a valve mechanism for steam-engines which will be simple, efficient, and positive in operation and wherein the use of wrist-plates and connecting-rods, such as are usually employed 15 in steam-engines of the Corliss type, is avoided.

The invention consists, substantially, in the construction, combination, location, and relative arrangement, all as will be more fully hereinafter set forth, as shown in the accompanying drawings, and finally specifically pointed out in the appended claims.

Referring to the accompanying drawings and to the various views and reference-signs appearing thereon, Figure 1 is a view in side 25 elevation, parts in vertical section, of a type of steam-engine showing the application thereto of a construction embodying the principles of my invention. Fig. 2 is a longitudinal sectional view of the steam-cylinder, 30 showing the arrangement of valves. Fig. 3 is an end view of the construction shown in Fig. 1, looking to the right of said figure. Fig. 4 is a broken detail view, in longitudinal section, of a main-valve-operating motor. Fig. 35 5 is a broken detail view, in side elevation, showing the relative arrangement of cut-off and tripping-cam sleeves for controlling the operation of the main supply-valve. Fig. 6 is a broken detail view in plan of the construction shown in Fig. 5. Fig. 7 is a broken detail view in section on the line 7 7, Fig. 1, looking in the direction of the arrows. Fig. 40 8 is a detached detail view of the sleeve for effecting the cut-off of the main valve. Fig. 45 9 is a similar view of the trip-cam sleeve.

The same part is designated by the same reference-sign wherever it occurs throughout the several views.

Reference-sign A designates the steam-cylinder of an engine; B, the main engine-shaft; C, the main piston; D E, the main supply-valves, one arranged at each end of the cyl-

inder, and F G the main exhaust-valves. These parts may be of the usual or any suitable or well-known type, construction, and 55 arrangement.

In the operation of steam-engines, and particularly engines of the Corliss type, it is usual to provide a rocking or wrist plate and connect the same by means of links or connecting-rods with the valves for actuating the latter. Such construction and arrangement, however, result in a comparatively slow movement of the valves in opening and closing. This is objectionable for the reason that 60 in order to secure the most efficient operation of the engine the steam-inlet valves should be quickly opened to their fullest extent and as quickly closed, and the exhaust-valve at one end of the cylinder should also be quickly 65 and fully opened immediately upon the opening of the steam-inlet valve at the other end of the cylinder. These results are not efficiently secured in the constructions employing the wrist-plate and link or rod connections therefrom to the valves. Moreover, in such construction it is difficult to vary the point of cut-off with variations of speed without the provision of special and complicated arrangements of connections. 70

It is the special purpose of the present invention to provide a construction and arrangement wherein the objections above noted are avoided and wherein the use of a rocking wrist-plate and the special cut-off varying connections is avoided and dispensed with. 75

In carrying out my invention I provide motors for actuating the main supply and exhaust valves. Preferably, and as shown, but to which, however, the invention is not limited 80 or restricted, I provide a separate motor 10 11 12 13 for each of the main-cylinder valves, the motors 10 and 13 serving for the steam-inlet valves D E, respectively, and the motors 11 and 12 serving for the exhaust F G. In 85 the particular form shown, to which, however, the invention is not limited, these valve-operating motors comprise cylinders having pistons 14 and rods 15 16 17 18, respectively, connected to the crank-arms 19 20 21 22 on 90 the stems of their corresponding valves D E F G. The motors 10, 11, 12, and 13 may be operated by either steam or compressed air or other medium. In practice I prefer to em- 95 100

ploy compressed air. The motor-operating medium is supplied to the motors through the supply-pipes 23 from any suitable or conveniently-arranged source, the pipes 23 delivering into chambers or casings 24, having suitable exhaust connections 25, and also connected to each end of the motor-cylinder through pipes or passages 26 27. The pipes or passages 26 27 deliver into the motor-cylinder at the extreme ends thereof, and arranged in said pipes or passages to seat outwardly from the motor-cylinder ends are the puppet-valves 28 29. At a point adjacent to, but somewhat removed from, the ends of the cylinder passages 30 31 are provided, opening communication between pipes or passages 26 27 and the motor-cylinders. Arranged in chambers or casings 24 are valves 32, constructed and arranged to open one end of the motor-cylinder to the supply and simultaneously therewith to open the other end of the cylinder to the exhaust.

In the operation of the valve mechanism of a steam-engine no special necessity exists for varying the point of opening or closing of the main-cylinder exhaust-valves or for varying the regularity of their movements. I will therefore describe the means for controlling the valves 32, which govern the motors 11 12, by which the main-cylinder exhaust-valves F G are operated.

Reference-sign 33 designates a shaft suitably and conveniently arranged and located and journaled in bearings 34, and from this shaft the valves of said motors 11 and 12 are actuated. In the particular arrangement shown, to which, however, the invention is not limited, shaft 33 is a rocking shaft, and suitable gearing is provided whereby said shaft is rocked upon each reciprocation of the main piston. As illustrative of an operative arrangement I have shown an arrangement for effecting the rocking movements of shaft 33 wherein an eccentric-rod 35 is pivotally connected at one end to a crank-arm 36 on said shaft and at the other end to an eccentric or wrist pin in a disk 37, mounted on and rotating with a shaft 38, which receives rotation from the main drive-shaft B of the engine through any suitable or convenient arrangement of gearing. It is evident, however, that any other suitable or convenient arrangement of gearing may be employed and conveniently arranged for effecting the rocking movement of shaft 33. From the construction shown it will be seen that upon each complete revolution of shaft 38, and hence of the main drive-shaft B of the engine, the shaft 33 is rocked from one of its limits of movement to the other. Mounted upon shaft 33 and suitably secured to rock therewith are the crank-arms 39 40, respectively connected by links 41 42 to crank-arms 43 44 on the stems of valves 32 of the cylinders which actuate and control the main exhaust-valves F G. From this construction it will be seen that the main exhaust-valves are positively and uniformly ac-

tuated upon each rotation of the engine-shaft. By suitably arranging the relative location of the arms 39 40 with reference to the direction and extent of rocking movement of shaft 33 it will be seen that the exhaust-valve at one end of the main cylinder may be closed or opened at any desired point in the operation with respect to the opening or closing of the exhaust-valve at the other end of the cylinder and also with respect to the movements of the main piston.

I will now describe the arrangement for securing the automatic regulation of the point of cut-off of the main steam-supply valves.

Suitably mounted upon shaft 33 to rock therewith are the sleeves 45, and adjacent to each of said sleeves I arrange the sleeves 47 48, said sleeves 47 48 being loosely mounted on said shaft. Pivotedly mounted on each of the sleeves 45 is an arm 49, arranged to project over the adjacent sleeves 47 48. The sleeve 48 is provided with a cam projection 50, having an inclined surface and terminating in an abrupt shoulder 51. The relative arrangement of the sleeves 45 and 48 is such that when the shaft 33 is rocked in one direction the pivoted arm 49, carried by sleeve 45, will ride up the inclined surface of cam projection 50 until the edge of said projection is cleared, whereupon said arm drops down behind the abrupt shoulder 51 of said projection and into position to engage therewith upon the reverse rocking movement of shaft 33, thus effecting a coincident and positive rocking movement of said sleeve 48 in the same direction. If desired, a spring 52 may be provided and arranged to act upon arm 49 to cause the same to certainly drop down in front of the shoulder 51 as soon as the arm 49 clears the projection 50. The sleeve 48 is provided with a crank-arm 53, which is pivotally connected through rod 54 to a crank-arm 55 on the stem of valve 32, which controls the motor through which the main steam-supply valves D E are actuated. Thus it will be seen that the valves 32 of the motors which actuate the main steam-supply valves are positively moved in one direction. Any suitable means may be provided for returning the said motor-valve to its initial position. For instance, I have shown a spring 56 (see Fig. 4) for accomplishing this object. It is obvious, however, that any other equivalent device may equally well serve the same purpose. The function of sleeve 47 is to disengage the arm 49 from engaging position with respect to the shoulder 51 of cam projection 50, and in order that this disengagement may be variably effected, according to the speed of the engine, in order to vary the point of cut-off of the main steam-supply valve said sleeve 47 is loosely mounted on shaft 33 and is provided in the periphery thereof with a trip-cam 57. The relative arrangement of sleeves 45 and 47 is such that during the rocking movements of said sleeve 45 the arm 49, carried thereby, will ride over the surface of sleeve 47, and hence in a path

enabling the trip-cam 57, carried thereby, to engage underneath said arm and elevate the same above the shouldered cam 50 of the co-operating sleeve 48. In order that the point 5 at which the disengagement of arm 49 from cam projection 50 may be varied according to the speed of the engine, I provide the sleeves 47 with crank-arms 58 and connect the same through rods 59 with crank-arms on 10 a rock-shaft 60, suitably and conveniently journaled. A crank-arm 61 on said rock-shaft is connected by a rod 62 with one end of a pivoted lever 63. To the other end of said lever is connected a rod 64, which is attached to the sliding sleeve of the governor H. By this arrangement it will be observed that shaft 60 is rocked more or less, according to the variations of speed of the governor, and hence of the engine. It will also be seen 15 that the displacement of sleeves 47 axially or rotarily with reference to shaft 33 and of sleeves 45 and 48 is thus dependent upon the positions to which shaft 60 is rocked, and hence upon the speed of the engine. In case 20 the engine speeds up beyond the desired point the shaft 60 is rocked through its crank-arm connections with the governor, and hence through rods 59 the sleeves 47 are rotarily displaced with reference to sleeves 45 48, so 25 as to bring trip-cam 57 into position to trip arm 49 from engagement with the shoulder 51 at a point earlier in the stroke of the main piston. The moment the disengagement occurs the spring or equivalent device 56, acting 30 upon the motor-valve 32, returns the said valve to its initial position, thus causing the main steam-supply valve to cut off. In this manner the cut-off takes place at a point earlier or later in the stroke of the piston, according 35 as the speed of the engine increases or decreases.

A convenient arrangement is shown for actuating the governor H by gearing the same up to shaft 38. It is obvious, however, that 40 the governor may be actuated in any other suitable or convenient manner from any rotating part of the engine.

It is stated above that pipes or passages 26 45 deliver into the motor-cylinders at the respective ends thereof and that outwardly seating valves 28 29 are arranged in said pipes or passages. It is also stated that passages 30 31 serve to open communication between the pipes or passages 26 27 and the motor-cylinder at points adjacent to but somewhat 50 removed from the ends of the cylinder, the object and purpose of this arrangement being to provide means for cushioning the motor-piston 14 at the ends of its stroke, and 55 thus to prevent pounding of the same against the ends of the cylinder. This result and purpose is effected, it will be observed, by the construction and arrangement above described. When the piston approaches the 60 end of its stroke, it will close the delivery end of passage 30 31 at the end of the cylinder toward which the piston is moving and through

which the air, steam, or other medium used on the previous stroke of the piston is exhausting. The closing of the passage 30 31 70 causes the seating of the valve 28 28, and therefore the air-pressure or steam remaining in the cylinder at that end will be compressed, thus cushioning the piston. When, however, the valve 32 is again actuated to 75 open that end of the cylinder to steam or air pressure, the previously-closed valve 29 opens, thus admitting such pressure to the cylinder to drive the piston in the opposite direction.

It is obvious that the particular location 80 and arrangement of the valve-actuating motors and of the shafts 38 33 and 60 are unimportant and may be changed or varied according to the exigencies and requirements of space and convenience without departure 85 from the spirit and scope of my invention.

From the foregoing description it will be seen that I provide an exceedingly simple and efficient arrangement of valve-gear for steam-engines wherein the point of cut-off of steam-supply is varied readily and easily by variations in speed, wherein when the steam-supply valve at one end of the cylinder is opened the exhaust-valve at the other end is immediately opened to its fullest extent, and where- 95 in the movements of the valves are effected positively and quickly.

While I have shown and described a specific construction and arrangement of apparatus embodying the principles of my invention, it is obvious that many variations and changes in the details thereof would readily occur to persons skilled in the art and still fall within the spirit and scope of my invention. I do not desire, therefore, to be 100 limited or restricted to the exact details shown and described; but,

Having set forth the object and nature of my invention and an apparatus embodying the principles thereof, what I claim as new 110 and useful and of my own invention, and desire to secure by Letters Patent, is—

1. In a steam-engine, main steam supply and exhaust valves having arms connected thereto for actuating the same, an independent motor for each valve, each motor comprising a cylinder and piston, connections between said pistons and valve-arms, and means actuated by variations in speed of the engine for controlling the movements of said main-steam-supply-valve-actuating motor-piston, 120 as and for the purpose set forth.

2. In a steam-engine, main steam supply and exhaust valves having actuating-arms connected therewith, a motor comprising a cylinder and piston, connections between said piston and the actuating-arm of said supply-valve, an independent motor comprising a cylinder and piston, said piston connected to the actuating-arm of said exhaust-valve, 130 means for controlling the supply of operating medium to said motors, and means for varying the supply of operating medium to the main-steam-supply-valve-actuating motor,

according to the speed of the engine, without varying the action of the main-exhaust-valve-actuating motor, as and for the purpose set forth.

- 5 3. In a steam-engine, a main cylinder having supply and exhaust valves, arms connected to said valves for actuating the same, an independent motor for each valve, said motors comprising cylinders and pistons, independent connections between the piston of each motor and the actuating-arm of its corresponding valve, means for controlling the supply of operating medium to said motor-cylinders, a speed-governor and connections actuated thereby for varying the supply of operating medium admitted to the operating-motor of the main supply-valve, according to the speed of the engine, as and for the purpose set forth.
- 10 4. In a steam-engine, a main cylinder having supply and exhaust valves, an independent compressed-air motor for each valve, connections between the piston of each motor and the corresponding valve of said main cylinder, a shaft, connections actuated by said shaft for controlling the supply of compressed air to said motors, and gearing for operating said shaft from the main drive-shaft of the engine, as and for the purpose set forth.
- 15 5. In a steam-engine, a main cylinder having supply and exhaust valves, a motor for actuating each valve, a rock-shaft, crank-arms mounted thereon to rock therewith, connections between said crank-arms and the exhaust-valve-operating motors for controlling the latter, disconnection devices actuated by said shaft for controlling the supply-valve-actuating motors, and means actuated by variations in the speed of the engine for varying the point of disconnection of said controlling means, as and for the purpose set forth.
- 20 6. In a steam-engine, a main cylinder having a supply-valve, a motor for actuating said valve, a rock-shaft, a sleeve loosely mounted thereon, crank connections between said sleeve and said motor for controlling the latter, means for detachably coupling said sleeve to rock with said shaft, and means controlled by the speed of the engine for varying the point at which said coupling is released, as and for the purpose set forth.
- 25 7. In a steam-engine, a main cylinder having a supply-valve, a motor for actuating said valve, a controlling-valve for said motor, a rock-shaft, a crank-arm loosely sleeved upon said shaft, a rod connecting said crank-arm and controlling-valve, a coupling for said sleeve whereby said sleeve may be coupled to rock with said shaft, and means actuated by variations in speed of the engine for automatically varying the point of uncoupling of said sleeve, as and for the purpose set forth.
- 30 8. In a steam-engine, a main cylinder hav-

ing a supply-valve, a motor for actuating said valve, a controlling-valve for said motor, a rock-shaft, a crank-arm loosely sleeved upon said shaft, and connected to said controlling-valve, said sleeved crank provided with a shoulder, a pivoted arm sleeved upon said shaft to rock therewith, said arm arranged to engage said shoulder, and means for automatically disengaging said arm from said shoulder, as and for the purpose set forth.

9. In a steam-engine, a main cylinder having a supply-valve, a motor for actuating the same, a controlling-valve for said motor, a rock-shaft, a crank-arm loosely sleeved upon said shaft and provided with a shoulder, connections between said arm and controlling-valve, a pivoted arm sleeved upon to rock with said shaft, said arm arranged when rocked to engage said shoulder and rock said crank-arm in one direction, whereby said controlling-valve is operated in one direction, means for yieldingly opposing said movement of the controlling-valve, and means for automatically releasing said pivoted arm from engagement with said shoulder, as and for the purpose set forth.

10. In a steam-engine, a main cylinder having a supply-valve, a motor for actuating said valve, a controlling-valve for said motor, a rock-shaft, a crank-arm having a shoulder and loosely sleeved upon said shaft, connections between said crank-arm and controlling-valve, a coupling-arm sleeved upon to rock with said shaft and arranged to engage said shoulder, a trip-cam for disengaging said arm from said shoulder, and means actuated by variations in speed of the engine for varying the point at which said trip-cam operates upon said coupling-arm, as and for the purpose set forth.

11. In a steam-engine, a main cylinder having a supply-valve, a motor for actuating said valve, a rock-shaft, a crank-arm provided with a shoulder and loosely sleeved upon said shaft, a pivoted arm sleeved upon to rock with said shaft, said arm arranged to engage said shoulder, a sleeve loosely mounted on said shaft and provided with a cam arranged to disengage said arm from said shoulder, a speed-governor, and connections between said governor and loose sleeve whereby the position of the latter upon said shaft may be rotarily varied according to the speed of the engine, thereby varying the point of detachment of said pivoted arm from said shoulder, as and for the purpose set forth.

In witness whereof I have hereunto set my hand, this 11th day of October, 1898, in the presence of the subscribing witnesses.

JOHN T. LINDSTROM.
